UNITED STATES PATENT OFFICE.

THOMAS ROBERTS, OF HAVERHILL, MASSACHUSETTS, ASSIGNOR OF ONE-HALF TO
JOSEPH E. DUBÉ, OF HAVERHILL, MASSACHUSETTS.

SEWING-MACHINE ATTACHMENT.

Application filed January 27, 1926. Serial No. 84,062.

This invention relates to certain improvements in means for finishing the edges of shoe uppers in the manner disclosed by the U. S. patent to Daniels #1,400,806, dated 5 Dec. 20th, 1921.

In performing the process disclosed in said patent, a galloon is folded about a cord and stitched to the outer side of the shoe upper near its edge and between the cord and the 10 edge, after which the edge portion of the upper is folded onto its inner side, so that the cord-containing portion of the galloon is held on the folded over edge of the upper, and the upper has a corded edge when finished, and 15 is known as a "French-cord" edge. Said patent discloses, as alternative methods, the assembling of the galloon and cord by folding the galloon about the cord and securing its opposite portions together close to the cord, 20 as a preliminary to the operation of stitching the galloon to the upper, and the assembling of the galloon and cord in this manner, at the time of stitching the same to the upper.

The method last referred to has been considered 25 advantageous over the other method, primarily because it dispenses with the operation of assembling the cord and galloon before they are stitched to the upper, but, not only was the means disclosed in said patent, 30 for assembling the cord and galloon at the time they are stitched to the upper, been found to be impractical, but, prior to my invention, no practical means, so far as I am aware, have been devised which enabled the 35 cord and galloon to be assembled and stitched to the upper by one operation, and in a manner which produced satisfactory results.

One of the essentials to satisfactory results 40 in the performance of the process, is that the galloon be drawn tightly about the cord and that it be secured in this position by stitches, and it is in this important particular that prior means for performing the operation of 45 assembling and stitching on at one time have failed, for, with a guiding means of the character illustrated in said patent, it is practically impossible for the operator so to guide the cord and galloon that the cord will be held firmly against the bottom of the fold in the 50 galloon and the latter will be drawn tightly over the cord and its folds secured together close to the same by the stitches which attach the galloon to the upper.

As a result of the failure to produce a prac-

tical means for assembling and stitching on 55 the cord and galloon at one operation, it has been the universal practice to assemble the cord and galloon previous to the attachment thereof to the upper. This has been done by folding galloon, or a narrow strip of textile 60 material, over a cord and adhesively connecting the opposite portions thereof, and it has been the practice for the galloon dealer to furnish the manufacturer with the galloon 65 thus prepared. As rubber cement, when used 70 as an adhesive for this purpose, would be objectionable, as likely to interfere with the operation of the sewing machine needle, a paste form of adhesive has been generally 75 employed. In practice much difficulty has 80 been encountered with the pasted galloon, for the reason that the paste is liable to lose its adhesive qualities, particularly if kept in stock for too long a time, so that the folds of 85 the galloon become separated and the cord 90 misplaced in consequence, making it practically impossible to attach it. Also, the paste tends to make the galloon stiff, and this stiffness is likely to increase with time. On account of this stiffness, difficulty has been 95 encountered in connection with the so-called turning operation, in which the galloon, after it has been stitched onto the outer side of the leather, is turned in onto the inner side thereof. This difficulty is encountered most frequently 100 in connection with patent leather, and on account of the stiffness of the galloon an undue strain is placed on the leather at the point when they are stitched together, so that the surface of the leather is frequently 105 cracked close to the line of stitches.

On account of the fact that the corded galloon is prepared for a special purpose, it is impractical for the galloon manufacturer to 110 prepare it in all the available shades, weights 95 and qualities, so that the choice of the shoe manufacturer of galloons available for the purpose is considerably restricted, and he is often unable to use the particular galloon 100 which he desires to use, for this reason. Furthermore, upper leather is likely to vary 105 in thickness, and, in order that satisfactory work may be performed, the thickness of the cord and galloon should correspond to the thickness of the upper. While this correspondence may be secured by varying the size of the cord according to required conditions, it has been considered impractical for the

dealer in corded galloons to provide the same with cords of different size.

These, and other objections to the prepared galloon may be avoided by providing a practical means for assembling any galloon and cord and stitching them to the upper by one operation, so that the shoe manufacturer may then employ any galloon and cord which is available.

- 10 In performing the process of said Daniels patent, it has been found practically necessary to cement the galloon to the inner side of the upper when the turning operation is performed, so that the operation of sewing on 15 the lining will be facilitated. When the galloon having its folds cemented together is employed, it is merely necessary to apply cement to one of these folds, but if the cord and galloon were assembled at the time they were 20 stitched to the upper by the method disclosed in said Daniels patent, a double cementing operation would be necessary to cement both folds of the galloon to the inner side of the upper.
- 25 The objects of my invention are primarily, to provide means, adapted for use in connection with a known type of sewing machine, which will fold the galloon about a cord and hold the cord securely against the bottom of 30 the fold, while the stitches are passed through the folded portions of the galloon in close proximity to the cord, and through the shoe upper, to attach the galloon thereto, so that the galloon will be drawn tightly about the 35 cord and secured in this position.

Other objects of my invention are to provide an attachment which will fold the galloon accurately, and in such a manner, that it will be so attached to the upper that when 40 the edge portion of the upper is folded onto its inner side, both folds of the galloon may be cemented to the inner surface by a single cementing operation.

I accomplish these and other objects of my 45 invention in the manner hereinafter described and illustrated in the accompanying drawing in which:

Fig. 1 is a perspective view of a sewing machine attachment embodying a preferred 50 form of my invention and showing the parts in position of use.

Fig. 2 is a plan view of the attachment partly in horizontal section.

Fig. 3 is a sectional view at line 3—3 of 55 Fig. 2.

Figs. 4 and 5 are sectional views at lines 4—4 and 5—5 respectively of Fig. 2.

Fig. 6 is an enlarged detail sectional view at line 5—5 of Fig. 2.

60 Fig. 7 is a sectional view at line 7—7 of Fig. 2.

Fig. 8 is a view of a section of the work after attaching and before folding, and

65 Fig. 9 is a section thereof after cementing and folding.

As the device which embodies the invention comprises a form of attachment adapted for use in connection with a common form of upper stitching machine, preferably of the cylinder type, it is considered unnecessary to 70 illustrate the same, except by indicating the machine parts directly associated therewith, which comprise the table T, the needle N of the sewing mechanism and the edge guide G.

According to my invention I provide an 75 attachment which comprises a bracket a, adapted to be mounted on a fixed part of the sewing machine, not shown, beneath the level of the work supporting surface of the table T, and having a flat arm a¹ formed integrally 80 therewith and extending horizontally adjacent the level of said surface. A guide plate b is secured on the arm a¹ by means of screws c and projects horizontally therefrom in transverse relation to the direction of feed 85 of the machine, and said guide plate is provided with an end portion having a semi-cylindrically formed face b¹, which extends from the front edge of said plate to an intermediate point therein, in the direction of the 90 feed, and a bore or cord passage b² is formed in said portion which extends in concentric relation to the face b¹. Said plate b is provided with approximately horizontal faces b³, b⁴ on its upper and under sides respectively, said faces extending continuously with the face b¹ and terminating in vertical guide shoulders b⁵, b⁶, which extend the entire width of the plate b. It is to be particularly noted in this connection that the width of the uppermost face b³, or the distance from the middle of the edge face b¹ to the shoulder b⁵, is substantially less than that of face b³, or the corresponding distance to shoulder b⁶, for reasons to be explained. A U-shaped 95 sheet metal casing e is extended about the entire end portion of plate b so as to enclose the faces b¹, b³, b⁴ thereof, said casing being held out of contact with said faces and having its opposite portions permanently connected 100 to the upper and under sides respectively of the plate b, the inner surface of the casing e being disposed in parallel relation to, and at such a distance from the faces b¹, b³, b⁴, that a U-shaped guiding passage g is formed therebetween, which is adapted to receive the galloon p and hold it in folded position as it is drawn therethrough, the guide shoulders b⁵, b⁶ being arranged to engage the edges thereof, as it is fed, so that the galloon will 105 be folded along a longitudinal line adjacent but at one side of its middle and the fold which engages the lower shoulder b⁶ will be wider than the other fold.

The front edge portion of the plate b is provided with an integral projection d, through which a tubular passage d¹ is formed, of the same size as the passage b², and at right angles thereto, the arrangement being such that a cord o may be drawn through the passage 110

*d*¹ and thence through the passage *b*² between the folds of the galloon *p*, which is being drawn through the passage *g*.

The end edge of the guide plate *b* is formed 5 to provide a cord-guiding face *b*⁷, which extends from the delivery end of the passage *b*², at the opposite side thereof from the face *b*¹, in a direction which is slightly oblique to the direction of said passage, and partly 10 across the same, in slightly convergent relation to the adjacent concave surface of the casing *e*, and then in parallel relation thereto, and practically in line with the line of 15 stitches which will be formed in the galloon, as it is delivered to the sewing mechanism, indicated by the needle *N*, the plate *b* and casing *e* being so supported that the delivery end of the face *b*⁷ will be in close proximity to the needle, and the delivery end of the 20 lower portion of the U-shaped passage *g* will be at the level of the surface of table *T*. The casing *e* tapers somewhat from its entrance to its discharge end, as shown in Fig. 7, so that the U-shaped passage *g* therethru tapers 25 correspondingly, the faces *b*³, *b*⁴ also being formed to converge slightly from the front to the rear end of face *b*¹. The rear portion of the face *b*⁷ is so formed with reference to the adjacent concave inner surface of casing 30 *e*, or passage *g*, that the distance from said face to said surface will correspond to the diameter of the cord plus the thickness of the galloon employed. That is the face *b*⁷ is held in sufficiently close proximity to the concave 35 face of casing *e* to press the cord firmly against the bottom of the fold in the galloon and thereby hold the latter firmly against said concave face, as the galloon and cord are drawn thru passage *g*, without causing undue 40 friction thereon.

With the above described construction, therefore, the cord and galloon having been placed in the relative position already described within the attachment, as they are drawn therethru, the galloon will be folded 45 longitudinally along a line adjacent, but at one side of its middle and the cord will be delivered between the folds of the galloon and pressed against the galloon at the line of the fold therein, which may be conveniently termed the bottom of the fold.

In performing the operation of attaching the galloon and cord, as thus assembled, to a piece of upper leather *q*, as indicated in Fig. 55 1, the leather piece, the edge portion of which will have been skived on its flesh side, will be placed on the table, flesh side up, with its edge portion resting on the casing *e* and its edge held against the edge guide *G*. The 60 folded galloon, with the cord therein, will be drawn from the passage *g*, so that they lie on the table beneath the leather, and the latter will be pressed firmly on the galloon by the usual presser foot, not shown. The feeding 65 mechanism of the machine will draw the gal-

loon and cord through the attachment as it feeds the leather, so that they will be stitched together by a row of stitches *s* which will pass thru the folds of the galloon close to the side of the cord opposite the bottom of the fold 70 in the galloon.

It is to be particularly noted that the relative arrangement of the leather guide and the galloon guide is such that the galloon will be attached to the grain side of the leather 75 in such a position that both folds of the galloon will project beyond the edge of the leather and the narrower fold will lie next the grain surface of the leather, as shown in Fig. 8. This is of vital importance for the following reasons: In the subsequent operation of finishing the edge of the leather, the edge portion thereof is folded inward along such a line that the cord containing portion of the galloon is held on the edge or top of the fold 80 thus formed. It has been found to be practically necessary to cement the inturned edges of the leather and galloon to the inner side of the leather before the lining is sewed on, consequently, a coating of rubber cement is 85 applied to the flesh side of the edge portion of the leather, and, at the same time, to the portion of the narrower fold of the galloon which projects beyond the skived edge of the leather, and the portion of the wider fold of 90 the galloon which extends beyond the edge of the narrower fold thereof. As a result, when the folding operating is performed, the edge portion of the leather will be folded 95 against its inner side, and adhesively connected thereto, and the edge portions of the galloon, to which the cement was applied, will also be folded against the inner side of the leather beyond its skived edge, as indicated in Fig. 9, so that all of these parts will 100 be cemented in the position into which they are folded. It is to be noted, however, that it is not essential that the edge portion of the narrower fold of the galloon project beyond the edge of the leather, so that cement 105 will be applied thereto when the edge portion of the leather is cemented, as it will be sufficient if the wider fold only projects beyond the edge of the leather, for the reason that if the edge portion of the wider fold adheres to the inner side of the leather, when the folding 110 operation is performed, it will hold the narrower fold flat against the leather.

With the above described attachment the cord and galloon will be positively guided, so that they will be assembled in the required relation and attached to the upper in the required position at one operation, which may be performed as rapidly as if the cord and galloon had been previously assembled, all the previously mentioned disadvantages of the prepared galloon being thereby avoided.

I claim:

1. A sewing machine attachment for the purposes described, comprising a casing 130

having a passage arranged to extend therethrough in the direction of the feed of the machine, a guide arranged to extend into said passage from one side thereof to divide the 5 same into opposite portions and an intermediate connecting portion, to permit a galloon to be folded lengthwise in U-form about said guide as it is drawn through said passage, said guide having a cord receiving passage 10 therein arranged to extend in the direction of said casing passage and opening thereto in position to deliver a cord between the folds of the galloon at the bottom of the fold therein, and cord-guiding means disposed in said 15 casing passage and terminating at the delivery end thereof, said means having a guiding face arranged to engage the cord, as it is drawn from the delivery end of said cord-receiving passage, and press the same against 20 the bottom of the fold in the galloon and the latter against the adjacent side of the casing passage at its delivery end, to permit the folds of the galloon to be stitched together close to the cord, while thus held, in close 25 proximity to the delivery end of the casing passage.

2. A sewing machine attachment for the purposes described, comprising a casing having a U-shaped passage adapted to extend 30 in the direction of the sewing machine feed and to receive a galloon and fold the same adjacent its middle portion as it is drawn therethrough and delivered to the sewing mechanism, a tubular guide located between the 35 opposite portions of said passage and terminating at its rear end adjacent the intermediate portion of the passage, and cord guiding means in said passage extending from the rear end of said tubular guide to the rear 40 end of the passage and having a guiding face arranged to extend convergently with the surface of the intermediate portion of said passage at its rear end, to hold the cord against the bottom of the fold in the galloon 45 as the galloon is delivered to the sewing mechanism.

3. A sewing machine attachment for the purposes described, comprising a casing hav-

ing a galloon receiving passage extending therethrough in the direction of the sewing machine feed, a guide plate arranged to extend into said passage from one side thereof and having an end face disposed adjacent the opposite side of said passage, to provide a U-shaped passage thru which the galloon is drawn, guiding faces at each side of said plate extending from the front to the rear end of said passage and arranged to engage the edges of the galloon and hold it in position in the passage, said guide plate having a cord-receiving bore extending from the front edge thereof and opening to said passage at the inner end of said face, and a guide in said passage extending from the inner end of said bore to the rear end of the passage and arranged to engage the cord as it is drawn from said bore and hold it against the bottom of the fold in the galloon and hold the latter against said side of the passage as they emerge from the passage. 70

4. A sewing machine attachment for the purposes described, comprising a casing having a galloon receiving passage extending therethrough, in the direction of the sewing machine feed, a guide plate arranged to extend into said passage from one side thereof and having an end face disposed adjacent the opposite side of said passage, extending for a portion of the length thereof, and about which the galloon will be folded as it is drawn therethrough, said guide plate having a bore adapted to receive a cord, and extending therethrough in proximity to said end face and opening at its rear end to said passage, in position to deliver the cord between the folds of the galloon, and supplemental guiding means disposed in said passage and having a face arranged to engage the cord as it is drawn from said bore and to deflect it against the bottom of the fold in the galloon and hold the latter against the side of said passage as it is delivered to the sewing mechanism. 80 85 90

In testimony whereof, I have signed my name to this specification.

THOMAS ROBERTS.
